UNITED STATES PATENT OFFICE.

MORRIS M. FAVISH, OF CHICAGO, ILLINOIS.

DESIGN FOR A SMOKER'S SET.

Application filed November 11, 1926. Serial No. 19,671. Term of patent 3½ years.

To all whom it may concern:

Be it known that I, MORRIS M. FAVISH, a citizen of the United States, residing at Chicago, in the county of Cook and State of Illinois, have invented a new, original, and ornamental Design for Smoker's Set, of which the following is a specification, reference being had to the accompanying drawings, forming part thereof.

I claim:

The ornamental design for a smoker's set, as shown.

MORRIS M. FAVISH.
